Attorney

UNITED STATES PATENT OFFICE.

HENRY L. PITMAN, OF WESTFIELD, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed January 3, 1923. Serial No. 610,410.

This invention relates to typewriting machines, and more particularly to computing mechanism to be actuated concomitantly with the typing of certain numbers. In typing bills for telephone service it is necessary to type separately the amounts of United States taxes on the individual taxable items, and it is desirable to be able to refer at any time to the total amount of the tax items in a definite period, such, for example, as a day or a longer period.

Heretofore it has been proposed to obtain the desired result by providing a standard typewriting machine with a special "5" key and a special "10" key for typing the corresponding numbers, and also with a single register of the same general type as the Veedee cyclometer but having its units wheel marked with "0" and "5" alternately, said register having means to carry over to the tens wheel each time the units wheel is advanced from "5" to "0". It was also proposed to provide means for advancing the units wheel one step for each actuation of the special "5" key and two steps for each actuation of the special "10" key.

An important feature of the present invention consists in the provision of improved means for actuating the units wheel by means of the special "5" and "10" keys.

As herein illustrated, the units wheel of the register is advanced one step at each oscillation of an operating arm connected by a link with one arm of a lever to be operated twice as far by the special "10" key as by the special "5" key.

The link and the adjacent arm of the lever form a toggle which is straightened by depression of the special "5" key, and such straightening of the toggle advances the units wheel one step. When, however, the special "10" key is actuated, the toggle is not only straightened to actuate the units wheel one step, but is bent in the direction opposite to the normal to draw the register-operating arm to its initial position, the arm being actuated again during the return movement of the special "10" key to advance the units wheel another step. Obviously, the use of the toggle, in the manner disclosed, renders it possible to operate the register by comparatively light pressure of the special keys.

Another feature consists in the provision of full-stroke devices for each of the special

keys to insure proper actuation of the register, said full-stroke devices being provided with novel adjusting means.

A further feature of the invention consists in the provision of improved means for mounting the register and the register-actuating devices on the frame of the typewriting machine.

It should be understood that the invention is not limited in scope to the mechanism disclosed nor to use in connection with the particular class of work described herein.

Other features and advantages will hereinafter appear.

In the accompanying drawings,

Figure 1 is a fragmentary side elevation, showing the invention applied to so much of a standard typewriting machine as is necessary for the purpose of illustration.

Figure 2 is a front view of the mechanism shown in Figure 1, a section being taken along the line 2—2 of Figure 1.

Figure 3 is a detail showing the position of the parts when the "5" key is in depressed position.

Figure 4 is a detail view similar to Figure 3, showing the position of the parts when the "10" key has been depressed sufficiently to straighten the operating toggle, and also showing the full-stroke mechanism associated with the special "10" key.

Figure 5 is a view similar to Figure 4, but showing the position of the parts when the depression of the special "10" key has been completed, the toggle being collapsed and the register-operating arm being returned to its normal position.

Figure 6 is a detail view showing the special "10" key and the associated full-stroke mechanism.

Figure 7 is a front view showing the full-stroke racks and the supporting means therefor.

The typewriting machine comprises the usual number and alphabet keys 11, and, in addition, a special "5" key 12 and a special "10" key 13, preferably arranged at the right-hand end of the keyboard. Upon depression of any one of said keys, a corresponding key-lever 14 will be depressed to cause a type-bar 15 to be swung upwardly and rearwardly to effect typing by means of types 16.

Upon depression of the special "5" key 12 to print the number "5" on a work-sheet,

the forward end of the corresponding key-lever 14 which overlies a pin 17 at the forward end of a substantially horizontal arm 18 of a bell-crank lever 19 will rock said lever 19 about its pivot 20 and swing a second arm 21 of the bell-crank lever from its normal position, extending upwardly and rearwardly from the pivot 20, to a substantially vertical position, as shown in Figure 3, thereby thrusting upwardly a link 22 which is pivoted at its lower end to said arm 21 and at its upper end to an oscillatory arm 23 which serves to actuate a register 24. It will be seen that the arm 21 and the link 22 form a toggle, indicated in general by 25, so that the actuation of the register may be effected by a comparatively light pressure of the key 12.

Upon the return movement of the key 12 the bell-crank 19 and the parts connected therewith will be restored to their normal positions by means of a spring 25^a connected at its forward end to the bell-crank 19 and at its rear end to any convenient fixed part of the machine.

The register 24 is of the same general type as the Veeder cyclometer, and comprises a series of number-wheels or dials 26. The register may be substantially the same as that disclosed in an application of Alfred G. F. Kurowski, Serial No. 599,221, filed November 6, 1922 (now Patent No. 1,574,906, dated March 2, 1926). Inasmuch as the register is to register the addition of 5 and 10 only, the wheel of lowest denomination is provided with "0" and "5" arranged alternately, and the carry-over mechanism is arranged to actuate the dial or wheel of next higher denomination each time a "5" on the dial of lowest denomination is shifted from the sight-opening 27 and replaced by the "0" immediately succeeding. It should be understood that the carry-over from the second wheel from the right is effected only when that wheel or dial has made a complete revolution, and the same is true of other wheels of higher denomination.

For actuating the bell-crank 19 when the special "10" key 13 is depressed, provision is made of a link 28 pivoted at its upper end to the forward end of the key-lever 14 corresponding to the key 13, and connected at its other end with the forwardly-extending arm 18 of the bell-crank lever 19 by means of a headed screw 29 passing through a slot 30 in the lower end of the link 28, and threaded into said arm 18 at a point intermediate the pin 17 and the pivot 20. It will be seen by reference to Figure 3 that the slot 30 is of such length that, upon depression of the special "5" key 12, the screw 29 will merely be shifted to the lower end of the slot 30 and will produce no result on the special "10" key 13. Upon depression

of the special "10" key 13, the bell-crank lever will be shifted first to the position shown in Figure 4 to actuate the arm 23 and consequently advance the dial of lowest denomination one step. Upon completing the depression of the key 13 the toggle will be bent to the front, as shown in Figure 5, and the oscillating arm 23 will be drawn down to its normal position, and upon the return of the key 13 to its normal position and the consequent return of the bell-crank 19, the arm 23 will be actuated again as the parts assume the position shown in Figure 4, and then arm 23 will be restored to its normal position with the other parts in the position shown in Figure 1.

To support the register 24, provision is made of a bracket 31 having a register-supporting shelf 32 extending outwardly over a downwardly-inclined member 33 forming part of the keyboard extension 34, the shelf lying close to the front of the main frame 35. The bracket also comprises a downwardly-extending portion or flange 36, which is secured to the side of the keyboard extension by screws 37 passing through the latter from the outside and threaded into the flange 36. It will be evident that the weight of the register will rest largely on the side of the keyboard extension and very little stress will be exerted on the flange 36 and the screws 37.

To support the bell-crank 19, its pivot 20, which is in the form of a screw, is threaded into a boss 38 formed on a bracket 39, which comprises a substantially vertical portion 40 and a horizontal portion 41, which engages the lower side of the main frame, and is held thereagainst by a foot 42 of the main frame secured in position by means of a screw 43 extending axially through the foot 42 and an opening in the portion 41 and threaded into the main frame. Provision may also be made of a screw 44 passing through another opening in the horizontal portion 41 and threaded into the lower part of the frame.

For the purpose of insuring proper actuation of the register by means of the special keys 12 and 13, provision may be made of suitable full-stroke mechanism. To this end, a pawl 45 is mounted by means of a pivot 46 on the key-lever 14 corresponding to the special key 12, and is held with the acting end of the pawl substantially in horizontal position by means of a spring 47 attached at one end to the pawl at the rear of its pivot 46, and at the other end to the key-lever near its forward end. The key-lever 14, corresponding to the key 13, is also provided with a pawl 48 mounted on a pivot 49, and yieldably held in centered position by means of a spring 50. The pawl 45 cooperates with a rack 51 formed on a block 52, which is provided with a depre-

sion 53 at the upper end of the rack, so that when the key 12 is in its normal position the pawl 45 will be held in its centered position by means of the spring 47. Upon depression 5 of the key 12, the rear end of the pawl will be swung upwardly by engagement with the block 52 above the upper end of the rack 51, so that, when the pawl is brought into engagement 10 with the rack, the point of the pawl will extend upwardly and will prevent any upward movement of the key 12 until the key has been depressed sufficiently to carry the point of the pawl below the lower end of 15 the rack 51, the pawl being released at this point and permitted to swing into centered position by means of a second depression 54 in the block 52.

It will be evident that as soon as the key 20 12 begins its return movement, the point of the pawl will be swung downwardly and will serve to prevent any downward movement of the key before it is returned to its normal position and the pawl 45 has been 25 restored to its normal position in the depression 53. To cooperate with the pawl 48 associated with the special key 13, provision may be made of a second rack 55 formed on the front of a block 56 which is provided 30 with depressions 57 and 58 corresponding to depressions 53 and 54, respectively, in the block 52. Each of the blocks 52 and 56 has a slot 59 at its upper end through which passes a screw 60 threaded into a guide-plate 35 61 for the key-levers 14. The arrangement thus described enables the racks 51 and 55 to be adjusted in a vertical direction to the proper range for co-operation with the corresponding pawls, and to be secured in such 40 position by the screws 60.

It has been found desirable also to provide 45 means for adjusting the blocks 52 and 56 forwardly and rearwardly to bring the corresponding racks 51 and 55 into the proper co-operative relation with the respective 50 pawls 45 and 48. To this end the blocks 52 and 56 are given a more or less wedge-like form, and back of each one of the blocks is inserted a wedge-like member 62 tapered in 55 the opposite direction, so that, by moving the blocks in one direction and the members 62 in the other, the blocks may be moved either forwardly or rearwardly. To enable such movement of the members 62, each of 60 them is provided with a slot 63 at its upper end. Such adjustment of the blocks 52 and 56 with the corresponding members 62 may be effected when the screws 60 are loosened, and the screws may then be tightened to 65 retain such adjustment. To prevent the blocks 52 and 56 and the corresponding wedge-like supporting members from being moved rearwardly when the pawls engage the corresponding racks, each member 62 is extended downwardly and is supported

against rearward movement by means of a small bracket 64 secured by means of screws 65 to the vertical portion of the bracket 39.

Variations may be resorted to within the 70 scope of the invention, and portions of the improvements may be used without others.

Having thus described my invention, I claim:

1. In a machine of the class described, in 75 combination, a register comprising a dial, two keys, and actuating means for said dial operable by one of said keys to advance the dial during the depression of the key and to return idly during the return of the key 80 and operable by the second key to advance said dial during depression of the key and also during the return of the key.

2. In a machine of the class described, in 85 combination, a register comprising a dial, dial-operating mechanism comprising a toggle, a key, and key-operable means to straighten the toggle to advance the dial.

3. In a machine of the class described, in 90 combination, a register comprising a dial, dial-operating mechanism comprising a toggle, a key, and key-operable means to straighten the toggle, once during the depression of the key and once during the return of the key, to advance the dial. 95

4. In a machine of the class described, in 100 combination, a register comprising a dial, dial-operating mechanism comprising a toggle, a key effective in one operation thereof to straighten the toggle to advance the dial 105 and to return the toggle to its normal position, and a second key effective in its downward movement to straighten the toggle and also to bend the toggle in the opposite direction preparatory to again straightening the 110 toggle and again advancing the dial during the return of the key.

5. In a machine of the class described, in 115 combination, a register comprising a dial, dial-operating mechanism comprising a toggle, a key, and key-operable means to straighten the toggle a plurality of times at each complete operation of the key.

6. In a machine of the class described, a 120 special key for typing a number, a register comprising a dial, and dial-actuating means comprising a key-controlled toggle to be straightened to actuate the dial during depression of the key and to be returned to normal position during the return of the key.

7. In a machine of the class described, a 125 special key for typing a number, a register comprising a dial, and dial-actuating means comprising a key-controlled toggle to be straightened to actuate the dial both during the depression of said key and during the return of the key.

8. In a machine of the class described, a 130 special key for typing a number, a register

comprising a dial, and dial-actuating means comprising a key-controlled toggle to be straightened and collapsed during the depression of the key and straightened and collapsed during the return of the key to advance the dial during both the depression and the return of the key.

9. In a machine of the class described, two special keys for writing numbers, one of said numbers being double the other, a register, an oscillatory arm for actuating the register, a toggle for oscillating said arm, and means for actuating said toggle once when the key of lower value is operated and twice when the key of higher value is operated.

10. In a machine of the class described, two special keys for writing numbers of different values, a register, an oscillatory arm for actuating the register, a toggle for oscillating said arm, and means for actuating said toggle so that the number of actuations of the toggle caused by depression of either one of said keys is proportional to the value of the key depressed.

11. In a machine of the class described, in combination, a register having a plurality of dials and an oscillatory arm to actuate the dial of lowest denomination, a pivoted lever, a link pivoted to said arm and forming with said lever a toggle to operate said arm, and means, including keys each typing a complete item at a single operation, for actuating said lever to straighten and collapse said toggle a number of times proportional to the value of the item typed.

12. In a typewriting machine, a register comprising a dial, special keys for advancing said dial to different extents, a key-lever for each of said keys, a full-stroke pawl on each of said key-levers, a full-stroke rack for each of said pawls, a vertically-movable support for each of said racks for individual adjustment thereof, a screw passing through each of said racks and through a slot in the corresponding support to secure them in adjusted position on a fixed part of the machine, and a bracket projecting from the lower part of the frame back of the lower ends of the supports to maintain the supports in proper position.

13. In a typewriting machine, a register comprising a dial, special keys for advancing said dial to different extents, a key-lever for each of said keys, a full-stroke pawl on each of said key-levers, a full-stroke rack for each of said pawls, a vertically-movable support for each of said racks for individual adjustment thereof, and a screw passing through a slot in each of said racks and through a slot in the corresponding support to secure them in adjusted position on a fixed part of the machine, the back face of each rack and the front face

of the corresponding support being inclined in opposite directions to enable adjustment of the racks forwardly and rearwardly.

14. In a typewriting machine having a frame with a forward keyboard extension having sides, in combination, special number-keys at one side of the keyboard extension, a register to be actuated by said keys, and a register-supporting bracket comprising a shelf resting on the top of the adjacent side of the extension and having a flange extending downwardly just inside said side and secured to the frame.

15. In a typewriting machine having a frame and feet secured to the bottom of the frame by screws passing axially through the feet and threaded into the frame, in combination, a register fixed on said frame, two special keys, register-actuating means including a pivoted bell-crank actuatable in proportion to the value of the special key depressed, and a bracket on which said bell-crank is pivoted, said bracket having a horizontal flange passing between the bottom of the frame and the forward foot on the same side as the special keys and secured in such position by means including the screw which holds the foot in position.

16. In a machine of the class described, in combination, a register comprising a dial, two keys, and actuating means for said dial operable by one of said keys to advance the dial during movement of the key in one direction only, and operable by the second key to advance the dial during depression of the key and also during the return of the key.

17. In a typewriting machine, a register comprising a dial and an oscillatory operating arm therefor to advance the dial a step at each oscillation, a reciprocable member constructed and arranged to impart a full oscillation to the register-operating arm during its complete advance stroke, and to impart a full oscillation to the register-operating arm during its complete retracting stroke, a key for writing a number, arranged, when operated, to cause the reciprocable member to be advanced a half stroke and returned to initial position, thereby imparting one full oscillation to the register-operating arm, and a key for writing a number twice as great as the first, arranged, when operated, to cause the reciprocable member to be advanced a full stroke and returned to initial position, thereby imparting two full oscillations to the register-operating arm.

18. In a typewriting machine, the combination of a register, a pair of type-keys, and means actuatable by one key, capable of operating the register only once for each complete key-operation, said means actuatable by the other key to operate the register twice in succession, once on the down stroke

of the key and again on the return stroke of the key.

19. In a typewriting machine, the combination of a register, a pair of type-keys, a toggle to operate the register, and means actuable by one key to straighten out the toggle to register once, and actuable by the other key to register twice in succession.

10 20. In a typewriting machine, the com-

bination of a register, a pair of type-keys, a toggle to operate the register, and means actuable on the down stroke of one key to straighten out the toggle to register once, and actuable by the other key to register twice in succession, by straightening out the toggle on both the down and the return stroke of the key.

HENRY L. PITMAN.
